SLIDE FASTENED TROUSER FLY
CONSTRUCTION

Albert B. Rhoads, Saegertown, and Edward F. Anderson, Meadville, Pa., assignors to Talon, Inc., a corporation of Pennsylvania

Application April 22, 1940, Serial No. 330,822

5 Claims. (Cl. 2—234)

This invention relates to slide fastened trouser fly constructions and particularly to the provision therein of new and improved tension means or reinforcing tape means.

5 It is an object of this invention to provide such an improved slide fastened trouser fly construction, embodying a tension member or reinforcing tape attached between the right and left flies in such manner as to be located totally outside the path of the slider of the slide fastener, making possible the use of a flat reinforcing tape without corded edge whereby to decrease the thickness of the fly construction over fly constructions embodying corded edge cross tapes.

10 15 It is a further object of this invention to provide such a construction wherein the reinforcing tape is applied in such manner that interference between the raw end edges of the tape and the interlocking fastener members of the slide fastener, that is, feeding of the fraying tape end threads into the meshing slide fastener interlocking members, is totally prevented.

20 25 It is a further object of this invention to provide such a construction which is particularly adapted to the use of a complete regular slide fastener comprising a pair of slide fastener stringers secured together at their lower ends by a bottom stop of conventional form.

25 30 It is a further object of this invention to provide a new and improved method of assembling and constructing trouser flies, wherein ease of assembly is substantially facilitated and the economy thereof substantially increased, due to the decrease of time and labor necessary for assembling the parts of the trouser fly, and achieving the construction thereof.

35 40 These and other objects and advantages of the invention will appear from the following description taken in conjunction with the accompanying drawings which form a part thereof, and will be pointed out in the appended claims.

In the drawings:

45 Fig. 1 is a fragmentary perspective view of a trouser fly construction embodying the principles of this invention;

50 Fig. 2 is a view similar to Fig. 1 and illustrating the assembly of the right and left flies or fly pieces with slide fastener stringers and reinforcing tape comprising the first step in a method according to this invention;

55 Fig. 3 is a view similar to Fig. 2, but illustrating a subsequent step in the method, wherein the reinforcing tape and attached slide fastener stringer are stitched down upon the left fly or fly piece;

Fig. 4 is a view similar to Fig. 3, but illustrating a following step in the method, wherein the free end of the reinforcing tape is attached to the right fly or fly piece, and the parts shown in Fig. 3 are stitched to the right and left fronts or front pieces of trousers;

5 Fig. 5 is a section taken substantially on the line 5—5 of Fig. 4;

Fig. 6 is a view similar to Fig. 2, but illustrating a former, known application of reinforcing tapes 10 in trouser flies; and

Fig. 7 is a view similar to Fig. 3, but illustrating an embodiment of this invention, wherein the initially applied raw end edge of the reinforcing tape is directed outwardly from the meshing interlocking fastener members, but projects outwardly beyond the side of the attached slide fastener stringer, the slide fastener being of the "regular" or closed end type embodying a conventional bottom stop.

20 Letters Patent No. 1,964,485, granted June 26, 1934, to Elliot O. Seaver, relate to trouser fly constructions and particularly the use of cross tape reinforcements between the stringers at the lower end of a slide fastener, and between the 25 attached right and left fronts or front pieces of the garment. As is explained in the specification of that patent, it was deemed necessary to provide such cross tapes with an upwardly directed beaded edge or reinforced edge, because of the contact, 30 consequent wear, and catching of the slider on that edge in its downward movement.

25 According to this invention, the reinforcing tape used is not a cross tape, as is the Seaver reinforcing tape, because it does not extend across the zone of movement or path of the slide fastener slider, but is spaced at one side of the zone of movement or path of the slider. This location of the reinforcing tape totally prevents the occurrence of catching or wear by reason of movement 40 of the slider. While such location of reinforcement tapes has been hitherto proposed, in the attachment of such reinforcement tapes, initially accomplished by the use of a staple, one of the raw end edges of the tape has been directed 45 toward the interlocking fastener members of the slide fastener and the slider, as shown in Fig. 6. This disposition of the raw end edge of the tape, upon the occurrence of substantial flexing of the garment fly portion, causes the threads of the tape 50 to ravel out and become enmeshed between the interlocking fastener members and the slider of the slide fastener. This caused objectionable hanging and binding of the slider at or below the reinforcing tape.

According to this invention, in the initial application of the reinforcing tape, the raw end edge of the tape is directed away from the interlocking fastener members of the fastener; the staple is applied to an intermediate portion of the reinforcing tape closely adjacent the interlocking fastener members of the slide fastener; the tape is then folded down outwardly over the staple and thereafter stitched simultaneously to one stringer tape of the slide fastener and to the left fly or fly piece of the garment. By applying the reinforcing tape in this manner, an intermediate double ply portion of the reinforcing tape is presented toward the interlocking fastener members of the fastener and the raw end edges thereof are substantially spaced from the meshing interlocking fastener members of the fastener and directed away therefrom, whereby interference of fraying tape end threads with the meshing interlocking fastener members is totally prevented.

In the drawings and in the following description, stitchings and other details which are not pertinent to this invention have been omitted in the interest or clearness of disclosure.

Referring to the drawings in detail and with reference particularly to Figs. 1 and 5, the left front or front panel of a trouser garment is generally designated 10, while the right front or front panel is generally designated 11. A waistband 12 is secured to the upper edges of the left and right fronts in known manner, one end of the waistband being provided with a buttonhole 14 and the other end thereof being provided with a co-operating button 14a. The right and left fronts or front pieces form the front of the garment, forwardly of the side seams and the inseams of the garment.

Attached in known manner to the inner edge of the left front 10 is the left fly 16, the stitching at its outer edge being designated 15, while the right fly 17 is attached in similar manner to the right front 11. One stringer tape 18 of a slide fastener is sewed to the left fly 16 by a double row of stitching 20, while the other stringer tape 19 is sewed to the fly 17, this latter stringer tape 19 being secured by a row of stitching 21 between the inner edge of the right front 11 and the right fly 17, as shown in Fig. 1.

The left front 10 and right front 11 are secured together below the fly portion by the center seam 22, and reinforcing stitching 23 of known form preferably extends transversely of the center seam 22 and through left front 10, right front 11, left fly 16 and right fly 17, as shown in Figs. 1 and 4.

A conventional shield 24 may be provided at the inner side of the right fly 17, as shown in Fig. 5, being secured thereto at one edge by the above-described row of stitching 21 and at the other edge by a row of stitching 25.

As shown in the drawings, the stringer tapes 18 and 19 are provided with reinforced edges 26, upon each of which is disposed in predetermined spaced relationship a row of interlocking fastener members 27. As shown in Fig. 7, a bottom stop 28 may connect the reinforced edges 26 of the stringer tapes 18 and 19 adjacent the lower end of each row of interlocking fastener members 27. The rows of interlocking fastener members 27 on each stringer tape 18 and 19 are progressively engaged and disengaged by longitudinal movement of the slide fastener slider 29, shown in Figs. 1 and 6.

The reinforcing tape, according to this invention, comprises a flat tape 30 of uniform thickness throughout and unprovided with such re-

inforced edge, as is disclosed in the above-mentioned Seaver patent. This obviation of the reinforced edge substantially decreases the thickness of the fly construction and the flexibility thereof.

Preliminary attachment of the reinforcing tape 30 is achieved by stapling it, by means of a staple 31, to the stringer tape 18 on the left fly 16. Formerly, the cross tape was located, as shown in Fig. 6, with one raw end edge thereof disposed toward the interlocking fastener members 27 of the fastener and toward the path of movement of the slider 29.

According to this invention, however, the initial attachment of reinforcing tape 30 is accomplished as shown in Fig. 2, the tape being laid upon the back surface of the lefthand fastener stringer 18 with its intermediate portion over the interlocking fastener members and both raw end edges directed away from the interlocking fastener members of the fastener. The staple 31 is then thrust through the reinforcing tape 30, the underlying fastener stringer tape 18 and the left fly 16, the staple being placed through an intermediate portion of tape 18 closely adjacent the interlocking fastener members 27.

After the preliminary attachment of the reinforcing tape 30, as shown in Fig. 2, the longer, or free, end of the reinforcing tape 30 (disposed toward the interlocking fastener members) is folded over upon the shorter, stapled end and over the stringer tape 18 and underlying left fly 16.

The next step comprises application of the two rows of stitching 20, described above, as shown in Fig. 3, to attach the transversely disposed reinforcing tape 30, the stringer tape 18 and left fly 16 together, as shown in Fig. 3. The head of the staple 31 is thus disposed between two plies of the reinforcing tape 30 and between the inner row of stitching 20 and the folded edge of the tape 30. This forms a pocket, in which the head portion of the staple 31 is embedded or disposed, which totally prevents further contact therewith.

Following stitching of the tape 30 to the underlying fastener stringer tape 18 and left fly 16, as shown in Fig. 3, the construction shown in Fig. 3 is turned over upon the right fly 17 and the longer, free end of the reinforcing tape 30 is laid down upon the right fly 17 and stitched thereto, preferably by zigzag stitching 32, as shown in Fig. 4. Thereafter, by means of stitching 15 and 21, the right and left flies are attached to the right and left panels 10 and 11.

As will be seen particularly in Figs. 1, 4 and 5, the raw end edges of the reinforcing tape 30 are both disposed a substantial distance from the path of the slider 29 and are both directed away from the path of the slider 29. The raw end edge at the short end of the tape 30 adjacent the staple 31 is preferably terminated within the outer row of stitching 20, as shown in Figs. 1 and 3, whereby there is no free portion to come in contact with other parts of the garment, with other garments, or with the hands of a garment wearer. The other, or longer, end of the reinforcing tape 30 being spaced from the path of the slider 29 by an intermediate continuous portion of the tape 30, effectively to prevent fraying of this raw end edge by slider action.

From the above description, it will clearly appear that we have provided a new and improved slide fastener trouser fly construction embodying a reinforcing tape which is of uniform thickness throughout and wherein the raw-end edges are both directed away from the path of the slide

- fastener slider and spaced substantially from the path of the slider, as is the entire reinforcing tape. Furthermore, staple 31, by which the cross tape is initially attached or located, is embedded 5 within the tape or disposed in the pocket formed therein, whereby it is invisible and insulated from contact with other parts of the garment and other clothing.
- It is, of course, to be understood that the above 10 description is merely illustrative and in nowise limiting and that we desire to comprehend within our invention all modifications included within the scope of the appended claims.
- Having thus fully described our invention, what 15 we claim as new and desire to secure by Letters Patent is:
1. In a trouser fly construction including overlapped right and left fly members attached respectively to the right and left front portions of a 20 trouser garment; a slide fastener stringer attached to each of said fly members, said stringers including rows of meshing interlocking fastener members with a slider longitudinally slidab thereon for engaging and disengaging said 25 fastener members, and a reinforcing tape folded over upon itself adjacent one end and secured to one stringer by stitching securing said stringer to one of said fly members, and a staple enclosed between plies of said reinforcing tape adjacent the 30 fold, the opposite end of said reinforcing tape being stitched to said other fly member, said reinforcing tape being spaced at one side of the path of movement of said slider, and the fold in said reinforcing tape being directed toward said interlocking fastener members, whereby both raw end 35 edges of said reinforcing tape are directed away from said interlocking fastener members and spaced laterally therefrom.
  2. In a trouser fly construction including overlapped right and left fly members attached respectively to the right and left front portions of a 40 trouser garment; a slide fastener stringer attached to each of said fly members, said stringers including rows of meshing interlocking fastener members with a slider longitudinally slidab thereon for engaging and disengaging said 45 fastener members, a reinforcing tape folded over upon itself adjacent one end and secured to one stringer by a double row of stitching securing said 50 stringer to one of said fly members, the opposite end of said reinforcing tape being stitched to said other fly member, said reinforcing tape being spaced at one side of the path of movement of said slider, and the fold in said reinforcing 55 tape being directed toward said interlocking fastener members with the raw end edge adjacent said fold overlapped by the intermediate portions of said tape and spaced inwardly of the outer edge of said stringer, and a staple securing the overlapped end portion of said reinforcing tape to the underlying stringer whereby both raw end 60 edges of said reinforcing tape are directed away from said interlocking fastener members and spaced laterally therefrom, and whereby the staple securing said reinforcing tape to said stringer is disposed in a pocket formed between plies of said reinforcing tape, said fold and the stitching securing said reinforcing tape, said stringer and 5 said fly member together.
  3. In a method of forming a trouser fly embodying a pair of fly members and a pair of slide fastener stringer tapes secured therebetween, the steps of stapling an intermediate portion of a 10 transversely disposed reinforcing tape to a slide fastener stringer tape closely adjacent the interlocking fastener members on the tape, folding over the other end of the tape and the staple, the end 15 of the reinforcing tape disposed toward said fastener members, and stitching the folded-over end of said reinforcing tape to said stringer tape in overlapping relationship to the other end thereof and the staple.
  4. In a method of forming a trouser fly assembly, assembling a pair of fly members and a pair 20 of complementary slide fastener stringers comprising tapes having thereon rows of interlocking fastener members, placing a reinforcing tape transversely across one stringer with both raw end 25 edges directed outwardly of the interlocking fastener members and one of said raw end edges disposed inwardly of the outer edge of the stringer, stapling an intermediate portion of said reinforcing tape to the tape of said stringer adjacent the 30 fastener members thereon, folding over the staple and the raw end edge disposed inwardly of the outer edge of said stringer, the other end portion of said reinforcing tape, securing the overlapped 35 portions together with stitching securing said reinforcing tape to said underlying stringer tape and one of said fly members, and stitching the free end of said reinforcing tape to said last-named fly member.
  5. In a method of constructing a trouser fly, 40 assembling a pair of trouser front portions, a pair of fly members, and a pair of complementary slide fastener stringers comprising tapes having thereon rows of interlocking fastener members, placing a reinforcing tape transversely across one stringer with both raw end edges directed outwardly of the interlocking fastener members, 45 stapling an intermediate portion of said reinforcing tape to the tape of said stringer adjacent the fastener members thereon, folding over the staple that end portion of said reinforcing tape disposed toward said fastener members, stitching the overlapped portions of said reinforcing tape together and to said underlying stringer tape and one of 50 said fly members, stitching the free tape end portion to the other fly member, and stitching the other fastener stringer to said last-named fly member while stitching to said trouser front portions the assembly comprising attached fly members, fastener stringers and reinforcing tape.

ALBERT B. RHOADS.
EDWARD F. ANDERSON.
